UNITED STATES PATENT OFFICE

DALLAS CASH, OF AKRON, OHIO

DESIGN FOR A HAT

Application filed June 4, 1929. Serial No. 31,543. Term of patent 3½ years

To all whom it may concern:

Be it known that I, DALLAS CASH, a citizen of the United States, residing at Akron, in the county of Summit and State of Ohio, have invented a new, original, and ornamental Design for a Hat, of which the following is a specification, reference being had to the accompanying drawings, forming a part thereof.

I claim:

The ornamental design for a hat as shown.

DALLAS CASH.
